FRANK W. MILES, OF ST. LOUIS, MISSOURI.

BRICK-CUTTING MACHINE.

1,105,989.

Specification of Letters Patent.

Patented Aug. 4, 1914.

Application filed June 16, 1913. Serial No. 773,924.

To all whom it may concern:

Be it known that I, FRANK W. MILES, citizen of the United States, residing at St. Louis, State of Missouri, have invented certain new and useful Improvements in Brick-Cutting Machines, of which the following is a full, clear, and exact description, reference being had to the accompanying drawings, forming a part hereof.

My invention has relation to improvements in brick-cutting machines; and it consists in the novel details of construction more fully set forth in the specification and pointed out in the claims.

In the drawings, Figure 1 is a front elevation of one end of a well-known type (the Raymond) of brick-cutting machine showing my invention applied thereto; Fig. 2 is a vertical cross-section on the line 2—2 of Fig. 1; Fig. 3 is an enlarged front elevation of a portion of the cutter-carrying frame and of the cutter-reel showing my invention in position; Fig. 4 is an enlarged vertical cross-sectional detail on the line 4—4 of Fig. 3; Fig. 5 is a plan of the platen carrying the impression or marking roller; Fig. 6 is a side elevation thereof; Fig. 7 is a cross-section on the line 7—7 of Fig. 6; Fig. 8 is an end view of the cam-head or wedge terminating the spindle of the marking roller, said view representing the head when the roller has been rotated or shifted from its proper initial position for marking the series of bricks cut from the clay column; Fig. 9 is a similar view showing the head righted or restored to proper position by the impact of the finger or tappet carried by the cutter-reel; Fig. 10 is a perspective of the finger or tappet which sets the marking roller right at the end of each forward or cutting stroke of the cutter; Fig. 11 is a cross-section on the line 11—11 of Fig. 6; and Figs. 12 and 13 are diagrammatic views respectively illustrating the marking roller in its wrong and correct positions preparatory to marking the bricks.

The present invention is particularly directed (though not restricted) to brick-cutting machines of the automatic type wherein a bar of clay is cut into bricks by means of a rotary cutter or reel provided with cutting wires, the frame carrying the reel having a

reciprocating motion parallel to the path of travel of the clay bar or column, whereby a given section of the bar is cut into a pre-determined number of bricks with each forward stroke of the frame. Under my invention I provide such reciprocating frame or member with a roller carrying a die which marks or impresses on the faces of the successive bricks so cut, a suitable trade-mark or other identifying mark or symbol peculiar to the manufacturer of the brick, the said roller being operated by the combined movements of the advancing column of bricks and the travel of the roller over the faces of the bricks with the backward or return stroke of the reciprocating frame aforesaid. As well understood by those skilled in the art, the rotary movement of the cutters or wires takes place simultaneously with the rectilinear or reciprocating movement of the frame and during the forward stroke of the latter. In such forward stroke the impression roller is idle, the marking of the bricks being effected only on the return or backward stroke of the frame, the forward advance of the clay bar and cut-bricks not being interfered with. On the forward stroke the cutter-supporting frame is supposed to move in unison with the advancing bar of clay; and were this possible in practice the marking roller which is in permanent contact with said bar would not be disturbed. In the actual operation of the machine however, the clay bar invariably gains on the feed-belt (owing to slippage) from a half inch to one inch and a half for a full forward stroke of the frame, and by reason of this gain the roller is disturbed or turned on its axis sufficiently to prevent the die thereof to imprint itself centrally on the faces of the bricks to be marked on the next backward stroke; and if the marking on the first brick is off center it follows that the same defect will attend the remaining bricks of the series.

It is therefore one of the objects of my invention to provide means for righting the roller before it begins to roll over the faces of the successive bricks, the adjusting device or "rectifier" by which the righting is accomplished being brought into action at the moment the bricks are severed from the clay

bar, or immediately prior to the beginning of the return stroke of the frame.

A further object is to provide a marking roller and rectifying attachment therefor which may be used on any type of brick-cutting machines of the general class here referred to, or on any type operating on a column or bar of clay (or other material) which is cut into bricks while such column or bar is in motion.

The improvement possesses further and other advantages which will be more fully apparent from a detailed description of the invention which is as follows:

- 15 Referring to the drawings, B represents a suitable base on which reciprocates the cutter-carrying frame or carriage F, the latter being in the form of a yoke terminating in circular heads or housings for the gear rings 20 1 forming the terminals of the reel to which the cutters 2 are secured, the cutters being in the form of wires disposed in series radiating from a central shaft 3 supported by the frame-heads, and having their terminals secured respectively to clamps or anchors 4 fastened to the shaft, and to anchors 5 secured to the bars 6 carried by the gear rings 1, the parts 1, 3, 4, 5, 6, collectively constituting the "reel" which rotates about the 30 axis of the shaft 3, the wires 2 constituting the cutters. The number of wires and the space between them may always be adjusted to the width of the brick to be cut, the clay column or column being cut either along planes 35 corresponding to the faces of the brick, or to the sides of the brick as in the present example, in which case the distance between consecutive wires corresponds to the thickness of the brick. Suspended loosely from 40 the axis of the reel are hangers 7 provided with platens 8 collectively forming a platform for the support of the brick column m, the delivery end of the frame F being provided with an extension platform 8' which 45 discharges the bricks m' cut from the bar onto a conveyer belt 9. The clay column or bar is fed to the platens 8 over a platform 8'' at the opposite end of the frame, from a feed-belt 10 and rollers 11, 11. The features 50 so far described (and others illustrated but not referred to) are well understood in the art constituting parts of a well known type of brick-cutting machine on the market. In this machine, as fully understood by those 55 familiar with the same, the clay column or bar m is advanced forward over the belt 10 (the material being discharged onto said belt from a suitable hopper not shown) onto the platforms 8'', 8, 8', the frame F (with its cutters) reciprocating back and forth during such advance, the cutters 2 severing the column and cutting it into the required bricks m' on each forward stroke of the frame; that is to say on each forward stroke of the 60 frame F, the cutter reel rotates a half revo-

lution permitting one set of wires to cut the clay bar (which keeps on advancing) the reel being stationary in so far as its motion of rotation is concerned, during the backward stroke of the frame. The reel (and its cutters) thus partakes of a rectilinear or reciprocating motion, and a rotary motion at right angles thereto during the cutting operation, the forward reciprocation being necessary inasmuch as the clay column is 75 constantly advancing, and the backward reciprocation being necessary to permit the cutters to resume their position opposite the next succeeding section or portion of the uncut bar. The platens 8 and their hangers 7 80 are of course properly spaced apart to permit the rotating wires 2 to pass freely between them. All this however, is well understood in the art, being referred to herein in a general way for a better understanding of 85 the invention proper.

In the present embodiment of my invention I mount beneath the next to the last platen 8 on the discharge side of the frame F, a suitable spindle 12, the same being secured by brackets 13 screwed to the platen, the brackets carrying suitable wearing brasses 14 held in position by screws s. Disposed in the path of travel of the clay column over the platen carrying the spindle 12 95 is formed an opening O opposite which there is mounted on the spindle 12 a roller or cylinder 15 provided with a trade-mark (Hytex) or equivalent die or symbol 16 which projects through the opening O and above 100 the plane of the brick-supporting face of the platen, the said trade-mark leaving its impression on the brick as the latter passes over the roller, or, (what amounts to the same thing) as the roller passes along the bottom 105 face of the severed brick. The periphery of the impression roller 15 is likewise provided with studs 17 adapted to engage the bottom face of the brick to prevent slipping between the parts, a purpose quite obvious from the drawing. At the outer end of the spindle 12 and projecting beyond the front edge of the platen 8 supporting the spindle is a substantially cylindrical head 18 having opposite pairs of faces a, a, converging to an edge e, 110 the edges of the opposing pairs of faces in turn diverging or making an angle with one another and converging toward a common groove or depression d disposed transversely to the plane of disposition of the edges e, e. 115 Coöperating with said faces a, a, and groove or way d, in a manner presently to appear is a curved finger 19 secured through its shank 19' directly to the bar 6 to which the cutters 2 are anchored, there being two such hooks 120 19, one for each set of cutters, said hooks operating as tappets or wipers. The faces a, a, may be compared to the faces of a wedge whose edge is the edge e, said faces acting as cams when engaged by the free end of the 130

hook 19 as presently to appear from a description of the operation of the invention, which operation is substantially as follows:

It is sufficient for our purpose to know that as the clay column *m* traverses the platens 8 from left to right (Fig. 1) the carriage or frame F by which said platens are carried reciprocates backward and forward without interfering with the advancing clay column, the cutters 2 severing a section of the column and cutting it up into bricks or blocks of predetermined size with each forward stroke of the carriage, the reel of which the cutters form a part having the necessary rotation imparted to it in such forward stroke to effect the cutting, by means of suitable gearing actuating the gear rings 1, but not necessary here to describe because well understood in the art. The marking roller 15 being mounted on one of the platens 8, it follows that the clay column will pass over it (or the roller under it) rotation to the roller being imparted only on the backward stroke of the frame F, because on the forward stroke the clay column and frame (and hence the roller) travel in unison and no rotation can be imparted to the roller (except that due to rotary or angular displacement by the gain of the clay column as presently to be seen). It will be seen that there are two dies 16 on the marking roller at points diametrically opposite one another, the cross-section of the roller being such that starting with one die against the center of the bottom face of one brick, the next die will leave its impression on the center of the face of the next brick, and as the roller rolls clockwise over the several bricks with the backward stroke of the carriage F, the several bricks will be properly marked, the stroke of the carriage being such as to carry the roller past the last brick marked and into engagement with the clay column *m* (Fig. 13). When the roller 15 occupies the position shown in Fig. 13, the frame F which carries said roller begins its forward stroke (to the right Fig. 1) at the conclusion of which the clay column is cut. In this forward stroke the frame and clay column are supposed to move in unison and were that possible in practice, it is apparent that the roller 15 would not be disturbed (that is to say, turned about its axis); but in the actual operation of the machine, owing to slippage between the feed-belt 10 and the clay column *m*, the latter gains anywhere from a fraction of an inch to over an inch and hence does not keep pace with the roller. The result is that a slight turn or rotary displacement is suffered by the roller the latter turning through an angle of several degrees, and when the carriage reaches the end of its forward stroke the rotary displacement of the roller is on the order represented in Fig. 12, that is to say,

the die 16 is no longer in central engagement with the face of the severed brick which is to receive the initial mark or impression. It may be stated in passing that the gain of the column results in the formation of "wedges" or waste blocks *m'* which are discarded as well understood in the art. The rotary displacement of the roller therefore, results from the differential of speed between the clay column and carriage, the column dragging the roller with it as it were, and hence turning it sufficiently to necessitate righting or centering of the roller under the first brick before the carriage proceeds in its backward stroke to roll the roller under the several bricks for marking the same. The dotted position of the roller in Fig. 12 represents its correct position and is brought to said position by a turning of the roller (see arrow Fig. 12) through an angle corresponding to the displacement, by means of the rectifying wiper or tappet 19. When the roller occupies its correct or center position, the depression *d* of the head 18 terminating the spindle 12 lies in the plane of rotation of the wiper 19 (Fig. 9); but when the roller is "off" or has suffered displacement the head 18 is turned so as to present one of either pair of the faces *a*, *a'*, to the wiper. The wiper rotating with the cutter-reel fouls a face *a* which acts as a cam or wedge, and the wiper riding over the incline of said face causes the head 18 (and hence the roller 15) to turn (Fig. 8) about its axis until the depression *d* comes into alignment with the path of sweep of the wiper (Fig. 9). By this time the roller is righted or centered properly to the brick on which the first mark is to be impressed, after which with the backward stroke of the carriage the roller marks the entire series of bricks, the studs 17 preventing any lost motion between the parts. In practice it makes no difference what degree of rotary or angular displacement the roller may suffer by reason of the gain of the advancing clay column, since one face *a* or another will always be presented to the finger or wiper 19 for restoring the roller. The wiper acts in point of time as the wires 2 are passing through substantially the center of the clay column, the cutting operation of course, consuming a comparatively short interval of time and taking place as the carriage is near the end of its forward stroke. The wiper emerges from the head 18 just about as the cutting is concluded or a trifle before, there being no possibility however, of angular displacement of the marking roller at this juncture, as the gain of the column between the time the wiper may emerge from the head, and the conclusion of the cutting operation is so slight as to be imperceptible, and hence negligible.

The attachment may, as quite obvious, be mounted on any machine of the type here described, or on any machine on which it could perform like service, and moreover need not be restricted in its application to brick-cutting machines or to a column of "clay." The face on which the trade-mark is impressed is the back of the brick.

Having described my invention, what I claim is:—

1. In combination with a reciprocating member traversed in a given direction by a column of material to be cut, means on said member for cutting the column into a series of sections with a movement of the member in one direction, independent supports for the severed sections carried by said member a marking roller on one of the supports traversing the sections with a movement of the member in the opposite direction, and means on the member for centering the die on the roller to the first section to be marked.
2. In combination with a reciprocating member traversed in a given direction by a column of material to be cut, cutters on said member operating across the path of travel of said column for cutting the latter into a series of sections with a movement of the member in the direction of the moving column, independent supports for the severed sections carried by said member a marking roller on one of the supports successively engaging the faces of the sections with a movement of the member in a direction opposed to the movement of said column and means on the member for centering the die on the roller to the first section to be marked.
3. In combination with a reciprocating member traversed in a given direction by a column of material to be cut, cutters on said member operating across the path of travel of said column for cutting the latter into a series of sections with a movement of the member in the direction of the moving column, a marking roller on the member permanently engaging the column for successively marking the sections with a movement of the member in a direction opposed to the movement of the column, and means on the member for centering the die on the roller, to the first section to be marked.
4. In combination with a member moving alternately in opposite directions and traversed by a column of material in one of said directions, means on said member for cutting the column into sections transverse to the direction of movement of the material, independent supports for the severed sections carried by said member a marking roller on one of the supports successively engaging the faces of the sections with a movement of the member in a direction opposed to the movement of the column, and means on the member for cen-

tering the die on the roller to the first section to be marked.

5. In a brick cutting machine, a reciprocating carriage provided with platens traversed by a clay column in a direction corresponding to one of the strokes of said carriage, cutters on said carriage for severing the column into bricks in paths across the direction of movement of the column, a marking roller on one of the platens engaging the bottom of the column and marking the bottom faces of the bricks at fixed points with a stroke of the carriage in a direction opposite to the movement of the column, and means on the carriage for presenting the die of the roller to the proper position against the first brick of the series.

6. In a brick-cutting machine, a reciprocating carriage provided with platens traversed by a clay column in a direction corresponding to one of the strokes of the carriage, a reel rotating about a fixed axis on the carriage and provided with wire cutters operating between the platens, a marking roller on one of the platens engaging the bottom faces of the column and of the bricks cut therefrom, a head on the spindle of the roller provided with pairs of opposing bevel faces converging to edges diverging from one another and forming a central transverse depression across the head, and a wiper on the reel co-operating with said faces and depression for the purpose set forth.

7. In a brick-machine having a reciprocating member provided with platens traversed in one direction by a clay column and a rotary cutter reel mounted on the member, a marking roller having a die operating through an opening of one of the platens and engaging the bottom faces of the bricks, a spindle for the roller, a terminal head on the spindle having a central transverse depression bounded by opposing pairs of bevel faces meeting in edges diverging from one another and from said depression, and a finger on the reel adapted to wipe against the faces with any rotary displacement of the roller thereby righting the roller, and pass through the depression, the righting of the roller properly centering the die thereof against the face of the first brick of the series to be marked, the parts operating substantially as, and for the purpose set forth.

8. In a machine of the character described, a reciprocating member traversed by a column of material to be cut, means on said member for severing the column into sections a marking roller on said member engaging said column and provided with a cam-head, said cam-head being out of contact with said column, in combination with a rectifying member periodically engaging said head, for the purpose set forth.

9. In a machine of the character described
operating to sever a moving column into a
series of bricks or sections, a rotary marking
roller engaging said column prior to the cut-
ting of the bricks and subjected to rotary
displacement by said column, and means for
righting said roller to properly present the
same to the faces of the bricks to be marked.

In testimony whereof I affix my signature,
in presence of two witnesses.
